UNITED STATES PATENT OFFICE.

SUEKICHI MOCHIDA, OF UPLAND, CALIFORNIA.

FRUIT-PICKER'S BAG.

1,147,419.

Specification of Letters Patent. Patented July 20, 1915.

Application filed February 21, 1914. Serial No. 820,357.

To all whom it may concern:

Be it known that I, SUEKICHI MOCHIDA, a subject of the Emperor of Japan, residing at Upland, in the county of San Bernardino 5 and State of California, have invented a new and useful Fruit-Picker's Bag, of which the following is a specification.

This invention relates to a bag to be carried by fruit pickers for receiving oranges, 10 lemons, and other fruit as it is picked from the trees.

The main object of the invention is to provide improved means for holding the lower end of the bag closed during the picking operation in such manner as to preserve 15 as far as possible the natural shape of the bag and provide for maximum carrying capacity.

Another object of the invention is to provide improved means for cushioning the 20 fruit in the bag to prevent abrasion, due to piling of the fruit on one another.

A further object of the invention is to provide improved means for cushioning or 25 easing the descent of the fruit into the bag.

The accompanying drawings illustrate an embodiment of my invention, and referring thereto: Figure 1 is a front elevation of the bag with the lower end in closed position. 30 Fig. 2 is a side elevation with the lower end open. Fig. 3 is a vertical section of the bag with the lower end closed. Fig. 4 is a plan view of the bag. Fig. 5 is a vertical section showing the means for elastically 35 supporting the apron at the top of the bag.

The bag 1, may be made of canvas or other suitable fabric, formed in tubular shape, and having its upper edge secured to a metal wire frame 2, whose rear portion 40 may be approximately straight and whose front portion may be curved to give a round form to the front of the bag. The canvas is rolled over the supporting frame 2, and seamed to retain it thereon, the roll at the 45 front portion of the frame being enlarged, and stuffed with cushioning material, such as hair or excelsior, to form a pad or cushion 3, for preventing abrasion of the fruit due to striking the front edge of the bag. An 50 apron 4 is attached at its front edge to the canvas bag in front of the cushion means 3, and extends obliquely downward and rearward toward the rear of the bag, being 55 spaced from the rear wall of the bag, leaving a space or opening 5 between the rear edge of this apron and the rear wall of the

bag, for passage of fruit into the bag. The rear edge of this apron is supported by an elastic tension member, for example, an elastic strip or cord 6, passed through a heading 7 on the rear edge of the apron, and secured at its ends to arms 8, extending downwardly from hangers 9, which support the bag frame 2 on the suspension means hereinafter described. Each of said hangers 65 consists of a wire bent in inverted V-shape and formed with a loop 12 at its upper end for receiving the suspension means, and bent at its lower portion to form eyes 13 surrounding the bag frame 2, the 70 arm 8 being a downward prolongation of one of the arms of this inverted V-shaped member. The other arm of each hanger is provided with a hook 16 for a purpose hereinafter set forth.

The suspension means consists of a strap or sling 18, of canvas or other suitable material, adapted to pass over the picker's shoulder, and provided with loops 19 at each end. A hook 20 connected to the loop 75 19 at one end of the suspension strap 18 engages the loop 12 at the upper end of the hanger at one side of the bag frame 2. The loop 12 of the hanger 9 at the other side of the bag frame is connected by rope or other 80 suitable means 21, to an eye 22 on the loop 19, at the other end of this suspension strap, this rope being tied to the loops 12 and eye 22, and being of such length as to provide 85 the requisite length for the suspending 90 means.

The bag 1 is open at the lower end, and means are provided for holding up the lower end to retain the fruit in the bag. For this purpose a cord 25 is attached to the 95 rear of the bag, at each side, near the lower end, and is passed through eyes 26 on the bag, said cord being provided at its free end with a ring or eye 27, to engage in the hook 16 aforesaid.

Partition cloths or pads 28 are preferably provided within the bag for separating the fruit in layers, said cloths or pads being slidably mounted on cords or retaining means 29, extending vertically within the bag, said cords or retaining means being for example, secured at their ends to the rear wall of the bag.

The bag 1 is provided on its rear face with a pad 30, adapted to rest on the ground 105 when the bag is being filled while the picker is in stooping position picking up fruit.

from the ground, thereby preventing damage to the fruit by falling on the bottom of the bag. This pad 30 is at the rear of the bag when in opened position, shown in Fig. 2, but at the bottom of the bag when in folded position, shown in Figs. 1 and 3.

The bag is used as follows: The suspending strap or sling 18 is passed over the picker's shoulder so that the bag remains in front of the picker. The partition cloths or pads 28 are drawn up and turned over back of the bag so as to extend between the bag and the body of the picker, serving at this time as a cushioning means for the bag.

The cords or retaining devices 25, are drawn up so as to bend up the lower end of the bag and gather in the side portions of said lower end, the rings 27 at the upper ends of these cords being caught onto the hooks 16, so as to hold the lower portion of the bag in bent up position and keep the bag in condition to retain the fruit. The fruit as it is picked is dropped or deposited on the apron 4 and rolls down through the opening 5 into the bag. The elastic tension means 6 serve as an elastic support for the apron to enable more effective operation thereof in easing or cushioning the descent of the fruit, this tension means, being connected to the arms 8 of the suspension hangers 9, is thereby retained in stretched condition and does not draw in or buckle the sides of the bag the pull of the suspension strap on said hangers serving to keep said hangers substantially vertical.

When the bottom of the bag has been filled in this manner one of the partition cloths or pads 28 is turned over from the outside of the bag to the inside thereof and pushed down on top of the fruit, so that the fruit which is then deposited in the bag will be separated by this pad from the fruit below it and prevent injury to the fruit by the fruit dropping onto that which is already in the bag or by rubbing of the fruit on one another. As the bag is filled these partition cloths are inserted at suitable intervals to separate the fruit into layers, and provide a pad for receiving the impact of the descending fruit.

It will be noted that when the bag is being filled the increase of weight in the bag tends to draw the retaining cords 25 tighter

and thereby gather the sides of the folded portion of the bag more tightly and fold them closer on the bag. The strain of these cords is taken directly by the hangers 9 and does not come upon the bag or the supporting frame 2 thereof.

When the bag is to be emptied the retaining cords 25 are removed from the hooks 16, and the lower end of the bag allowed to fall to position shown in Fig. 2, the cords 25 drawing through the eyes 26 so as to allow the gathered portion of the sides of the bag to be straightened out, giving the full discharge opening for the bag.

What I claim is:

1. In a fruit picker's bag, the combination of a bag frame, a bag hung therefrom, an apron extending obliquely downward and inward from said frame, an elastic tension means connected to the lower edge of said apron, and means mounted on said frame for tensioning said elastic means.

2. In a fruit picker's bag, the combination of a frame, a bag hung therefrom, a hanger at each side of the bag mounted on said frame, suspension means connected to the hangers on the sides of the frame, each of said hangers having a downward extension, an apron extending from the frame obliquely inward and downward, and a tension means connected to the lower edge of said apron and connected at its ends to the said downward extending arms of the respective hangers.

3. In a fruit picker's bag, a partition pad mounted on the bag to move vertically therein, and having one edge free to enable it to be turned over one edge of the bag.

4. In a fruit picker's bag, the combination of vertical guide means, and a plurality of partition pads mounted to move vertically in said guide means at one edge of said pads, and having their other ends free to enable them to be turned over one edge of the bag.

In testimony whereof, I have hereunto set my hand at Upland California this 11 day of February 1914.

SUEKICHI MOCHIDA.
